Primary Examiner — Cynthia M. Chin(74) *Attorney, Agent, or Firm* — Larson & Larson, P.A.;
Frank Liebenow; Justin P. Miller(57) **CLAIM**

The ornamental design for a solar catamaran boat, as shown and described.

DESCRIPTION

FIG. 1 is an upper-left-front perspective view of a solar catamaran boat showing my new design;

FIG. 2 is an upper-left-front perspective view thereof;

FIG. 3 is an upper-left-front perspective view thereof with the top folded;

FIG. 4 is an upper-left-front perspective view thereof with the top and seat folded;

FIG. 5 is an upper-left-rear perspective view thereof with both the top and seat deployed;

FIG. 6 is an upper-left-rear perspective view thereof with the top partially retracted;

FIG. 7 is an upper-left-rear perspective view thereof with the top retracted;

FIG. 8 is an upper-left-rear perspective view thereof with the top and seat retracted;

FIG. 9 is a front view thereof with top and seat deployed;

FIG. 10 is a rear view thereof with top and seat deployed;

FIG. 11 is a left side view thereof with top and seat deployed; the right side view is a mirror image of the left side view; and,

FIG. 12 is a top view thereof with top deployed.

The broken lines shown are included for the purpose of illustrating portions of the solar catamaran boat which form no part of the claimed design.
